UNITED STATES PATENT OFFICE.

GEORGE WILLIAM KORN, OF CHICAGO, ILLINOIS.

DESIGN FOR A PATTERN FOR TOY ROCKERS.

SPECIFICATION forming part of Design No. 25,041, dated January 7, 1896.

Application filed May 23, 1895. Serial No. 550,451. Term of patent 3½ years.

To all whom it may concern:

Be it known that I, GEORGE WILLIAM KORN, a citizen of the United States of America, residing at Chicago, in the county of Cook and State of Illinois, have invented and produced a new and original Design in Patterns for Toy Rockers, of which the following is a specification.

This invention relates to patterns for toy rockers of that class which may be formed from cardboard by suitably cutting and folding or bending the same and which are known as "kindergarten" toys, the invention itself being the design for the pattern along whose lines the cardboard is to be cut and folded.

The invention is shown in a single figure, in which—

A represents a sheet of cardboard of suitable size, on which the pattern is drawn or printed, the pattern or design itself being made up of solid and dotted lines, as follows: B is a central dotted line. C C are curved solid lines meeting at c and symmetrical with reference to the line B, and C' C' are curved

solid lines approximately parallel to the lines C C and meeting at c', the points c c' being joined by a short solid line C², forming a continuation of the line B. Dotted lines B' B', parallel to the central line B, lie on opposite sides thereof and equidistant therefrom, and a transverse dotted line B² intersects the lines B' B' at points approximately at their centers. Solid lines D D' D², at right angles to the lines B' B', extend outward from said lines respectively to the corresponding curved lines C' C', and a solid transverse line D³ joins the lines C' C' and intersects the dotted lines B' B'.

The essential feature of this design is the symmetrical arrangement with reference to the central line B of the curved lines C C, having a form approximately like that shown.

What I claim as new is—

The design for a pattern for a toy rocker substantially as shown and described.

GEORGE WILLIAM KORN.
